UNITED STATES PATENT OFFICE

160,149

COVERED CONTAINER

Louise D. L. Coloman, Los Angeles, Calif.

Application October 14, 1949, Serial No. 5,479

Term of patent 3½ years

(Cl. D58—11)

To all whom it may concern:

Be it known that I, Louise D. L. Coloman, a citizen of the United States, residing in the city of Los Angeles, county of Los Angeles, and State of California, have invented a new, original, and ornamental Design for a Covered Container, of which the following is a specification, reference being had to the accompanying drawing, forming a part thereof.

Fig. 1 is a front elevational view of a covered container showing my new design;

Fig. 2 is a side elevational view thereof;

Fig. 3 is a top plan view;

Fig. 4 is a bottom plan view;

Fig. 5 is a rear elevational view; and

Fig. 6 is an exploded perspective view, to a smaller scale, showing the cover in a raised position.

I claim:

The ornamental design for a covered container, as shown.

LOUISE D. L. COLOMAN.
